UNITED STATES PATENT OFFICE.

CHRISTOPHER C. SHARP, OF CHICAGO, ILLINOIS.

APPARATUS FOR GENERATING OZONE.

SPECIFICATION forming part of Letters Patent No. 481,676, dated August 30, 1892.

Application filed September 18, 1891, Serial No. 406,073. (No model.)

To all whom it may concern:

Be it known that I, CHRISTOPHER C. SHARP, a citizen of the United States, residing at Chicago, in the county of Cook and State of Illinois, have invented a new and useful Improvement in Apparatus for Generating Ozone, of which the following is a specification.

My invention relates to an improved method of and apparatus for generating ozone and applying the same for therapeutical purposes.

In the drawings, Figure 1 is a view in the nature of a diagram showing a machine for generating electricity, a stool for the patient, having a platform forming one terminal and upon which the feet of the patient rest, and an ozone-generating attachment forming the other terminal; and Fig. 2, a central longitudinal section, enlarged, of the ozone-generator.

The electric generator A may be an induction-machine of well-known or suitable pattern, that illustrated being of the Wimshurst type; or it may be a generator of any other character suitable for my purpose. The induction-machine in the drawings is shown to be geared to an electric motor B, which drives it, the motor being propelled from any convenient source, (not shown;) but of course the said generator may be driven by any other convenient power.

C is an ozone-generator, which I prefer to construct, as illustrated in Fig. 2. The device there shown comprises a flask-shaped bulb, round in cross-section, of glass or other suitable insulating material, and formed in two sections *t* and *t'*, screwed together. The large end or base *s* of the bulb is flat and provided with an opening *s'*, through its center, and an opening *s''*. The bulb terminates at its reduced end in an open flaring mouth *r*. The section *t* and the section *t'* as far as the line *x* are covered on their inner surfaces with foil or sheet metal *q* and serrated at the edge *x*, as shown. Within the bulb is an electrode in the form of a semi-spherical metal cup *D*, having a metal boss *D'*, the cup being of less diameter than the inner surface of the bulb. Through the center of the boss *D'* of the cup is an opening *p'* for a screw *p*, which extends through the opening *s'* of the bulb into a support *E* of insulating material, which, as shown may be suspended from a ceiling. The screw

p operates to clamp the bulb between the cup and support to hold the parts in fixed relation and the cup equidistant around its serrated edge from the inner circumference of the bulb. The inner surface of the cup is provided with numerous metal points *o*, which are formed by inserting tacks with pointed heads through perforations in the cup, which thus also form points *o'* on the outer side of the cup, as shown. One of the conducting-wires *n* from the electric generator extends through the opening *s''* in the bulb, and is secured to the metal boss *D'*, the ozone-generator thus forming one terminal of the generator A.

F is a stool having a metal or metal-covered foot-rest or platform *F'*, and mounted upon insulating-supports *y*. On the platform *F'* is a binding-post *m*, to which the conductor *m'* from the electric generator is secured, the platform thus forming the other terminal of the generator A. The relative positions of the ozone-generator and stool should be such that when the patient sits upon the latter the mouth *r* of the bulb will be conveniently accessible to his mouth.

In operation the patient places his mouth close to but out of contact with the mouth *r* of the ozone-generator, and the electric generator being set in motion a current of electricity will pass between the terminals C and *F'* through the body of the patient. The effect of the current passing from the points of the cup *D* is to generate, from the air in the bulb, ozone, which escapes at the mouth *r* of the bulb and is inhaled by the patient. The strong odor peculiar to ozone which is perceived when the apparatus is in operation, indicates a profuse generation of ozone, and the concentration and discharge thereof thorough the contracted mouth *r* causes the peculiar advantage of enabling the patient to obtain the full benefit of its effects in a manner which can not be equaled by any other method of which I am aware.

In the practice of my invention I employ an induction-machine A, capable of generating a large quantity of electricity, and a patient sitting on the stool F with his mouth near the mouth of the bulb C and feet on the platform *F'*, besides inhaling the ozone, affords a conductor for the passage of a large amount

of electricity without shock or any disagreeable effect.

While I have thus far obtained the best results in the practice of my method with the use of the apparatus constructed as shown and described, the apparatus may be modified in the matter of details of construction of the devices for generating the current of electricity and for generating the ozone without departing from the spirit of my invention.

What I claim as new, and desire to secure by Letters Patent, is—

1. The method of simultaneously generating ozone and applying it to a body, which consists in applying one terminal of the electric generator to the body, maintaining the other terminal out of contact with the said body, generating ozone at the non-conducting terminal, and closing the circuit between the ozone-generating terminal and the body by the current of ozonized air, substantially as described.

2. In a machine for generating and applying ozone, the combination, with an electric generator, of an ozone-generator forming one only of the electric terminals and having a discharge-opening for the ozone, the other terminal being adapted for application to the body, substantially as and for the purpose set forth.

3. In an electric apparatus, the combination, with the electric generator, of an ozone-generator forming one only of the terminals and comprising a bulb of insulating material having a discharge-opening and an electrode in the bulb, to which the conducting-wire leads, provided with projections of conducting material, the other terminal being constructed for application to the body, substantially as described.

4. In an electric apparatus, the combination, with the electric generator, of an ozone-generator forming one of the terminals and comprising a bulb of insulating material having a contracted discharge-opening and lined on its inner surface with conducting material and an electrode in the bulb, to which the conducting-wire leads, provided with pointed metal projections, the other terminal being constructed for application to the body, substantially as described.

5. In an electric apparatus, the combination, with the electric generator, of an ozone-generator forming one of the terminals and comprising a bulb of insulating material having a contracted discharge-opening and lined on its inner surface with conducting material and an electrode in the bulb, to which the conducting-wire leads, comprising a metal cup provided on one of its surfaces with pointed metal projections, the other terminal being constructed for application to the body, substantially as described.

6. In an electric apparatus, the combination, with the electric generator, of an ozone-generator forming one of the terminals and comprising a bulb of insulating material having a contracted discharge-opening and lined on its inner surface with conducting material and an electrode in the bulb, to which the conducting-wire leads, comprising a metal cup provided on its inner and outer surfaces with pointed metal projections, the other terminal being constructed for application to the body, substantially as described.

CHRISTOPHER C. SHARP.

J. W. DURENFORTH,
M. J. FROST.

Correction in Letters Patent No. 481,676.

It is hereby certified that in Letters Patent No. 481,676, granted August 30, 1892, upon the application of Christopher C. Sharp, of Chicago, Illinois, for an improvement in "Apparatus for Generating Ozone," an error appears in the printed specification requiring the following correction, viz.: In line 18, page 2, the compound word "non-conducting" should read *non-contacting*; and that the said Letters Patent should be read with this correction therein that the same may conform to the record of the case in the Patent Office.

Signed, countersigned, and sealed this 4th day of October, A. D. 1892.

[SEAL.]

Countersigned:

W. E. SIMONDS,
Commissioner of Patents.

CYRUS BUSSEY,
Assistant Secretary of the Interior.
